AMALGAMATOR

George M. Hollenback, Los Angeles, Calif.

Application December 12, 1941, Serial No. 422,643

5 Claims. (Cl. 259—85)

This invention relates to amalgamators, and particularly to a device wherein particles of alloy are not reduced, which results in a more stable amalgam and trituration rendered less critical.

An object of the invention is the provision of a device wherein trituration is not timed but accurate control thereof is maintained in a novel manner.

Another object is the provision of an amalgamator which is inexpensive in cost of manufacture, attractive in appearance, efficient in operation, easily maintained in a sanitary condition, of small weight and size, and generally superior to amalgamators now known to the inventor.

With the above mentioned and other objects in view, the invention consists in the novel and useful provision, formation, construction, association, and relative arrangement of parts, members, and features, all as shown in one embodiment in the accompanying drawing, described generally, and more particularly pointed out in the claims.

In the drawing:

Figure 1 is a perspective view of the amalgamator.

Figure 2 is a sectional view on the line 2—2 of Figure 1, and on an enlarged scale, and,

Figure 3 is a fragmentary sectional view on the line 3—3 of Figure 1.

Referring now to the drawing, the amalgamator includes a base 1, to which is secured in any appropriate manner, a motor 2, usually of the universal type and adapted to run on either A. C. or D. C. current. The motor shaft 3 carries a worm 4 adapted to mesh with gear 5 carried by shaft 6. The shaft 6 in turn is provided with a worm 7. The worm 4 and gear 5, as well as ends of the shafts 3 and 6, are housed within a casing 8. Mounted on the base 1 is casing 9 which in turn supports casings 10 and 11. A shaft or spindle 12 is passed through casings 9, 10 and 11, being suitably journaled therein and said shaft is provided with a gear 13 adapted to mesh with worm 7. The upper end of the shaft 12 is provided with a cross pin 14. The casing 11 is formed to support a platform 15, which platform in turn carries a post 16. This post is centrally bored at 17 to receive a stud 18. The stud in turn carries an arm 19 having squared ends 20 and 21. The end 21 has secured thereto, sleeve 22. A rod 23 is passed through sleeve 22 and said rod carries a ring or ledge 24. The opposite end of the rod is reduced in diameter and screw-threaded at 25, for connection with a pestle 26.

A mortar 27 is carried on shaft 12, with the cross pin 14 received within the confines of a base groove 28 of said mortar. This mortar is internally provided with an annular curved base groove 29. This construction provides a central extension 30 formed with a bore 31. A distributor 32 includes a pair of wire members 33 and 34 secured to a ring 35, the ring provided with a stud 36 for reception in the bore 31. The wires 33 and 34 are so bent as to conform in curvature to certain portions of the annular groove of the mortar, as best shown in Figure 1. The mortar is provided with spaced vertical pins or prongs 37 and the pestle is provided with spaced radial pins or prongs 38.

The shaft 12 is reduced in diameter and provided with a worm at 39. This worm meshes with a gear 40 on shaft 41. This shaft is suitably journaled in ends of casing 42. Shaft 41 is provided with a threaded area 43 and said threaded area is exposed by slotting the casing 42, as shown at 44. Along an edge of the casing at the slotted portion and adjacent the threaded area of the shaft are a series of graduations 45. These graduations are marked so as to indicate a certain number of revolutions of the mortar when the device is in operation, as hereinafter set forth. Secured to the casing 42 are a pair of brackets 46 and 47, between which extends a rod 48. Carried on the rod 48 is an adjustable slide or nut 49. This slide is provided with a threaded face 50 for engagement with the threaded area 43 of the shaft. The slide is provided with an elongated slot 51 and a coil spring 52 positioned within said slot is adapted to force the threaded face 50 into engagement with the threads of the shaft (see Figure 3). A handle 54 permits an operator to disengage the slide from the threaded shaft and to adjust the slide to any position desired on the rod 48. The slide is provided with a pointer 55 in order that the slide may be positioned relative to certain selected indications 45.

Secured within a recessed portion 56 of the base is an electrical switch 57. A switch arm 58 on the top surface of the base 1 is adapted to actuate the switch. The arm 58 carries an up-standing pin 59 positioned in the path of movement of the slide 49.

The operation, uses and advantages of the invention are as follows:

This device is useful in the production of stable amalgam. The particular alloy and mercury to be used is placed within the groove of mortar 27. If it has been determined that a certain number

of revolutions of the mortar and pestle are necessary for trituration, the slide 49 is released from the threads of shaft 41 and moved to some selected indication 45. Ordinarily each indication represents ten (10) revolutions of the mortar. Thus, if the graduations are in tens, with every tenth graduation of longer length than the others to distinguish their graduations, it is evident that if the slide travels ten (10) graduations, one hundred (100) revolutions will be made by the mortar. As universal motors vary in their operating characteristics, this device, depending as it does upon revolutions rather than timing, is capable of producing more uniform results. It has been found, for instance, that universal motors will run from 15 to 25% faster on a direct current than on an alternating current. Thus, having determined the number of revolutions to be made by the pestle to produce a given amalgam, the slide 49 is positioned at a proper point, as indicated by the graduations, for engagement with the threads of the shaft 41. The switch 58 is then moved to the right, viewing Figure 1, and the motor, if connected with a source of current supply, will then rotate spindle 12 through the worm and gears to cause rotation of the mortar. This spindle 12 will likewise rotate shaft 41. As the mortar rotates, the pestle is rotated, due to the fact that the pins 37 will contact with the radial pins on the pestle to rotate the pestle. As trituration is dependent upon the type of alloy used and the amount of weight placed on the pestle, weights 60 are provided for this purpose. These weights are formed with a central bore so as to fit over an end of the member 23 and rest upon the ledge 24, as shown for a single weight. The mortar and the pestle will rotate in the same direction, and it has been found that this produces a better and more stable amalgam as the particles of alloy are not reduced. The slide 49 will travel as the mortar and pestle revolve, until such time as the slide contacts pin 59 and snaps the switch lever from an "on" position to an "off" position. It will be found upon removing the mortar assembly that every particle of the alloy will be coated with mercury and that no hand mulling is necessary.

The distributor which comprises the two wire members 33 and 34 tends to move the amalgam within the mortar and likewise maintain the working surface of the mortar in a clean condition.

The mortar is easily cleaned, and if necessary the surface of the mortar and pestle may be ground by using a small amount of carborundum powder and water, followed by revolving the mortar and pestle in the manner heretofore described.

It is evident that the parts of the device are readily disassembled, in that the stud 18 carrying arm 19 may be removed from the socket of post 16, which movement will permit a lifting of the pestle from the mortar. The mortar rests on

the cross pin 14 and may be lifted therefrom. It is to be observed from Figure 2 that the shaft of spindle 12 extends a short distance beyond the cross pin 14 and that this portion is received within a central bore of the mortar. This construction gives rigidity to the mortar when carried on the spindle.

I claim:

1. An amalgamator including a mortar having an annular groove, a pestle for the mortar confined in said groove having a diameter less than the transverse width of the groove and free to rotate therein, means for rotating the mortar, and supporting means for said pestle permitting lateral play thereof in the groove as the mortar rotates.

2. An amalgamator including a mortar having an annular groove, a pestle for the mortar confined in said groove having a diameter less than the transverse width of the groove and free to rotate therein, means for rotating the mortar, supporting means for said pestle permitting lateral play thereof in the groove as the mortar rotates, and said pestle being vertically slideable and rotatably mounted through said supporting means.

3. An amalgamator including a mortar having an annular groove, a pestle for the mortar confined in said groove having a diameter less than the transverse width of the groove and free to rotate therein, means for rotating the mortar, supporting means for said pestle permitting lateral play thereof in the groove as the mortar rotates, said pestle being vertically slideable and rotatably mounted through said supporting means, and supplemental means carried by the pestle to vary the vertical pressure thereon.

4. An amalgamator including a mortar having an annular groove, a pestle for the mortar confined in said groove having a diameter less than the transverse width of the groove and free to rotate therein, means for rotating the mortar, supporting means for said pestle permitting lateral play thereof in the groove as the mortar rotates, said pestle being vertically slideable and rotatably mounted through said supporting means, and intermittently engaging means on the mortar and pestle adapted to continuously rotate the pestle.

5. An amalgamator including a mortar to receive an alloy having an annular groove with a central upright, a pestle for the mortar confined in said groove having a diameter less than the transverse width of the groove, means for rotating the mortar, and a distributor comprising a wire projecting radially from the central upright of the mortar to a point adjacent the outer wall of the groove and provided with a downwardly and inwardly curved extremity for disposing the alloy between the pestle and mortar during rotation of the mortar.

GEORGE M. HOLLENBACK.
